SPLIT CONNECTOR FOR ELECTRICAL CONDUITS

James H. Cannon and Robert J. Cannon, Los Angeles, Calif.; said Robert J. Cannon assignor to said James H. Cannon

Application July 29, 1940, Serial No. 348,260

8 Claims. (Cl. 285—123)

Our invention relates to electrical fittings and is directed specifically to a connector for electrical cords and conduits with special reference to a conduit connector.

Connector fittings are employed in various electrical installations in laboratories, moving picture studios, radio studios, public address systems, aircraft circuits and the like to interconnect electrical cords and rigid or flexible conduits, or to connect such cords or conduits with fittings on machines, instruments, panels, instrument boards, and walls. Usually these connectors enclose electrical fittings such as plugs or receptacles to which electrical conductors or fittings are attached. For example, when such a connector is employed to releasably connect a flexible conduit with a receptacle in a panel, the connector houses a plug complementary to the receptacle.

A conventional connector is so constructed that in assembly the conductors or wires in the conduit must be connected to the associated plug fitting or receptacle fitting while the fitting is outside the connector, the fitting being subsequently inserted in the connector. Such an assembly procedure requires excess length in the conductors and necessitates crowding the conductors into loops when the fitting is inserted in the connector. For subsequent inspection, which may be frequent where the connector is employed in aircraft, it is necessary to remove the electrical fitting from the connector to expose the connections of the conductors with the fitting terminals, and of course after each inspection the excessively long conductors are again crowded into the connector when the electrical fitting is replaced.

Repeatedly crowding the conductors into loops after inspection has several bad results. The loops may flutter excessively, especially under conditions of vibration characteristic of aircraft. The friction and bending involved break down the structure of the insulation in which the conductors are encased. The conductors tend to crowd together, causing pressure that further damages the insulation and in addition favors short-circuits. Finally, the repeated bending of the conductors may eventually cause fatigue failure of the conductors themselves, especially at the solder points where applied heat may have crystallized the conductors.

One object of our invention is to provide a conduit connector so constructed as to avoid the necessity of providing excess length in con-

ductors when electrical plugs or receptacle fittings are to be mounted in the connector.

A further object of our invention is to provide a conductor connector that may be opened conveniently for inspection without the necessity of disturbing either the conductors in the connector or the fitting in the connector to which the conductors are attached.

A still further object is to provide a longitudinally split connector that is normally of rigid, unitary construction, but may be opened laterally for convenient access to the interior of the connector whenever desired. One feature of our invention is that the exposure of all the wires necessary for testing circuits may be accomplished entirely from one side of a panel.

It is common for the fitting in a connector to be polarized with respect to the complementary fitting that is releasably engaged by the conduit fitting. In other words, the two fittings may be mechanically arranged to cooperate at only one rotary position of one fitting relative to the other, so that the same plug elements of one fitting always contact with the same receptacle elements of the other fitting. Since the electrical fitting in the conduit connector is usually non-rotatably mounted in the conduit connector, the polarization of the fittings limits the connector to some predetermined rotary position when the connector is in service. Quite frequently the predetermined rotary position of the connector is unsuitable for a particular installation, or it becomes desirable for some reason to change the rotary position of the connector after the connector has been in service for a period of time. For example, an angular fitting of the type commonly used where a cable is disposed at an angle to a line of plug insertion is usually designed for some given angle of the cable relative to the polarity of the plug insertion, but frequently the given angle is not feasible because of limited space or some obstruction at the given angle. A further object of our invention is to design a conduit connector that is adjustable through a plurality of rotary positions relative to the associated electrical fitting. Such adjustability in a connector makes it possible to manufacture and stock a single fitting for a number of different installation requirements and makes a given fitting flexible in the sense that the fitting may be readily adapted to various installation requirements.

In conventional connectors of the types heretofore employed, considerable labor is involved in the replacement of important parts of the struc-

ture and usually resoldering of wires to contacts is necessary. One object of the present invention is to simplify such replacement and to eliminate the necessity of disturbing soldered joints.

In one practice of our invention we have the further object of providing a split connector that is especially adapted for use on the end of a rubber covered cord.

Other objects and advantages of our invention will be apparent from the following detailed description, considered with the accompanying drawings.

In the drawings which are to be taken as illustrative only:

Fig. 1 is a view in longitudinal section of the preferred form of our connector;

Fig. 2 is a transverse section taken as indicated by the line 2—2 of Fig. 1;

Fig. 3 is a transverse section taken as indicated by the line 3—3 of Fig. 1;

Fig. 4 is a fragmentary section taken as indicated by the line 4—4 of Fig. 3;

Fig. 5 is a transverse section taken as indicated by the line 5—5 of Fig. 1;

Fig. 6 is a perspective view partly broken away showing the preferred form of the invention partially dismantled for inspection;

Fig. 7 is a side elevation of an angular form of our connector;

Fig. 8 is a section taken as indicated by the arrow 8 in Fig. 7, with various optional dispositions of the connector shown in dash-dot lines;

Fig. 9 is a side elevation partly in section of a cable connector constructed in accord with our invention;

Fig. 10 is a transverse section taken as indicated by the line 10—10 of Fig. 9;

Fig. 11 is a transverse section taken as indicated by the line 11—11 of Fig. 9; and

Fig. 12 is a perspective view of a deformable wedge employed in the structure shown in Fig. 9.

The embodiment of our invention shown in Figs. 1 and 6 is a straight connector adapted to releasably connect a flexible conduit 10 to a panel 11. Three conductors 12 from the flexible conduit 10 are connected in the connector to three female contacts 13 of an electrical receptacle 15, the electrical receptacle 15 being adapted to receive three prongs 16 of a complementary plug fitting 17. The plug fitting 17 is mounted in a cylindrical body 18 having a flange 19. The cylindrical body fits into an aperture 20 in the panel 11 and is attached to the panel by suitable screws 21 through the flange 19.

The present invention includes an inner cylinder 22 that is a unitary part of the electrical receptacle 15, the inner cylinder housing an insulating body 23 in which the contacts 13 are embedded. The insulating body 23, which may be made of a suitable synthetic plastic is enlarged to engage an inner annular shoulder 22a of the inner cylinder 22 and is backed by a rigid insulating disc 24 through which the contacts 13 extend. The disc 24 is in turn secured by a split ring 25 that seats in a complementary annular recess 26 of the inner cylinder. It will be noted that the material of the body 23 overhangs the ends of the contacts 13 to prevent relative movement forward of the contacts and that rearward shoulders 27 of the contacts abut the disc 24.

The inner cylinder 22 telescopes into the cylindrical body 18 of the receptacle 15 and for polarization the inner cylinder 22 may be formed with a longitudinal recess 28 in its periphery to

receive a complementary pin 29 that is mounted in the cylindrical body 18. If it is desirable to attach the connector in a positive but releasable manner to the cylindrical body 18, a common practice in aircraft construction, the connector will be provided with a gland nut 30 adapted to screw onto the cylindrical body 18. In the preferred construction such a gland nut is mounted on the inner cylinder 22. Thus, the inner cylinder may have a continuous peripheral shoulder 31 for engagement by an inner annular flange 32 of the gland nut 30 that rotatably embraces the inner cylinder.

The connector of our invention includes a shell 35 that constitutes the body of the connector, and a feature of our invention is that this shell is longitudinally split into two separate sections 36. Preferably the shell is divided into the two sections on a diametric plane and preferably one of the sections has longitudinal lips 37 at the junctures and the other section forms complementary recesses 38 to receive the lips, such a construction resulting in the two sections interlocking in a rigid unitary manner when pressed together.

One of the features of our invention is the concept that by splitting the connector shell 35 into separable longitudinal sections, the shell may engage the inner cylinder 22 in a releasable manner provided the shell and inner cylinder have cooperating shoulders arranged to be engaged when the two shell sections are assembled together and to be disengaged when the shell sections are disassembled. As those skilled in the art well know, such shoulders may be provided by various expedients such as forming lugs, recesses, annular ribs, and annular grooves. In our preferred construction we employ a plurality of lugs in cooperation with a plurality of complementary recesses whereby we may not only interlock the shell 35 and the inner cylinder 22 against relative axial movement, but also against relative rotation. As a further refinement serving a useful purpose in the preferred form of our invention, we arrange the lugs and cooperating recesses at equal circumferential spacing in a symmetrical pattern about the axis of the inner cylinder, so that the inner cylinder and shell may be locked at selected positions of relative rotation. The lugs may be either on the inner cylinder 22 or on the shell 35.

In accordance with these concepts, we provide in the preferred form of our invention a circumferential series of equally spaced lugs 40 on the inner cylinder 22 and a complementary series of recesses 41 in the corresponding inner surface of the shell 35, there being six such lugs and recesses in the preferred form of our invention. By making the lugs tapered, for example, pyramidal in general configuration, and making the lugs relatively small we achieve a construction in which the shell sections 36 may be readily engaged with the inner cylinder 22 and disengaged by simple lateral movement relative to the inner cylinder. For convenience in manufacture and assembly the inner flange 32 of the gland nut 30 may be formed with notches 42 dimensioned to clear the lugs 40, whereby the gland nut may be assembled to the inner cylinder 22 by longitudinal movement past the lugs into engagement with the peripheral shoulder 31. It is important to note that in the absence of such notches 42 it would be necessary to increase the inner diameter of the inner flange 32 and correspondingly to increase the diameter of the whole assembly

including the plug fitting 15 on the panel 11. The conception of employing the notches 42 is of special importance for installations where fittings must not exceed specified diameters.

It is apparent that the construction described to this point provides for the shell sections to interlock when pressed together and when so interlocked to effectively engage the inner cylinder 22, and that after the parts are so assembled, full access to the interior of the shell may be had simply by lifting one of the shell sections away from the other. To complete this particular combination it is necessary to add some suitable means to clamp the two shell sections together. In the practice of our invention various clamping expedients may be employed, but the arrangement shown in the drawings will be found especially advantageous.

The depicted clamping means includes a conical shoulder 43 and adjacent threads 45 formed in the shell 35, which are adapted to cooperate with a complementary clamping ring or nut 46. The clamping ring 46 is preferably knurled for convenience in manual manipulation and has a conical clamping surface 47 at one end complementary to the conical shoulder 43 whereby the ring when screwed onto the threads 45 against the conical shoulder 43 has the required constrictive effect to hold the two shell sections together.

In the particular arrangement shown in the drawings the described clamping combination is at the end of the shell 35 that embraces the inner cylinder 22, but the clamping combination may be placed at a more central position on the shell, if desired. We prefer the end position because it places the clamping action close to the lugs 40 and because the usual threaded coupling means that is necessarily employed with such a connector may be relied upon to clamp the other ends of the shell sections 35 together. Thus, Fig. 1 shows a conventional gland nut 48 at the end of the flexible conduit 10 screwed onto threads 50 at the end of the shell 35. It is to be noted that the threads 45 that cooperate with the clamping ring 46 are relatively large in diameter so that the clamping ring 46 may engage the threads 45 but be large enough in diameter to clear the threads 50 at the end of the shell.

If the gland nut 48 is unscrewed from the shell 35 and retracted onto the flexible conduit 10, and if in addition the clamping ring 46 is unscrewed from the threads 45 and moved past the threads 50 onto the flexible conduit, either or both of the shell sections 36 may be lifted away to expose the interior of the connector. See Fig. 6 showing the gland nut 48 retracted, the clamping ring also retracted, and one shell section 36 removed from the connector. In any event, it is unnecessary to disturb the wires 12 or the fitting 15. It is apparent that inspections of the interior of the connector may be made conveniently, rapidly, and without the usual detriment to the wiring. All the wires are accessible from one side of the panel 11 for making tests. It is further apparent that in the original assembly of the wiring to the electrical fitting 15 it is not necessary to provide any excess length in the wires 12.

One important feature of the described construction is that various parts of the connector may be freely replaced without the necessity of disturbing any soldered joints. In fact every part of the assembly except the disc 24 may be quickly replaced without any soldering operation.

Figs. 7 and 8 show a 90° connector that is constructed precisely in the manner above described

except that the shell 35a is in the form of an elbow. It is in this embodiment of our invention that the rotative adjustment of the shell relative to the inner cylinder is especially advantageous, since the connector may be turned to any one of six rotative positions relative to the polarization of the fitting in the connector. Fig. 8 in full lines shows the shell in one disposition and shows in dot-dash lines five other dispositions to which the shell may be turned.

Another type of connector employed in one practice of our invention is illustrated in Figs. 9 to 12. This connector generally designated 60 is shown connecting a three-conductor rubber cord 61 to the previously described plug fitting 17 on the panel 11. The connector 60 has an inner cylinder 62 exactly like the inner cylinder 22 of the first described form of our invention, the inner cylinder 62 having a shoulder means in the form of a series of spaced peripheral lugs 63 and having an annular peripheral shoulder 65. A gland nut 66 corresponding to the previously mentioned gland nut 30 has the usual notches to clear the lugs 63 and is adapted to abut the peripheral shoulder 65 to hold the connector on the plug fitting 17.

The contents of the inner cylinder 62 are identical with the contents of the previously described inner cylinder 22, including three female contacts 67 in an insulating body 68 together with a disc 10 and a split ring 11 to hold the insulating body in the inner cylinder. Three wires 12 from the rubber cord 61 are soldered respectively to the three contacts 67.

The connector 60 has a connector shell generally designated 75 that is in the form of an elbow and is split into two separable sections 76 having the usual interlocking ribs and recesses along their junctures. The shell 75 is similar to the previously described shell 35 of Fig. 1 in having a conical shoulder 77 and threads 78 for cooperation with a clamping ring 80 identical with the previously described clamping ring 46. The shell 75 is unlike the shell 35, however, in having a single continuous recess or inner annular groove 81 instead of the previously mentioned series of recesses 41. It is important to note that the substitution of the continuous recess for the series of spaced recesses results in complete freedom for rotational adjustment of the shell 75 about the axis of the inner cylinder 62.

The end of the shell 75 that receives the rubber cord 61 is formed with a conical mouth 82 and when the connector is in service a split ring generally designated 83 is seated in the conical mouth. The split ring 83 comprises two semi-soft rubber wedge members 85, each of which, as indicated in Figs. 9 and 12, is of tapered configuration and has inner serrations 86. A special gland nut 87 that is removably threaded on the end of the shell 75 has an inwardly directed annular flange 88 that is adapted to overhang and abut an outer face 90 of the split ring 83.

In the procedure of installing the connector 60 for service, the wires 12 of the rubber cord 61 are soldered to the contacts 67 and the two shell sections 76 are assembled and clamped together by the clamping ring 80. The two wedge members 85 are then placed in the conical mouth 82 of the shell to form the split ring 83 and the gland nut 87 is threaded onto the shell sufficiently to place the wedge members 85 under considerable pressure. When placed under pressure in the manner contemplated, the wedge members 85 grip the rubber cord 61 in a

constrictive manner and the serrations 86 of the wedge members engage the rubber cord in a manner to prevent the rubber cord from being shifted longitudinally outward from the connector.

It will be noted that the special gland nut 87 has not only the function of holding the shell sections 76 together, but also the function of placing the split ring 83 under pressure to grip the rubber cord 61. It will also be noted that the wedge members 85 comprising the split ring 83 not only serve to grip the rubber cord and to seal the end of the connector but also serve as a cushion or protector to keep the rubber cord 61 from contact with the metal of the gland nut 87. When the rubber cord is bent or allowed to hang at an angle from the end of the connector, the wedge members 85 keep the metal edges of the gland nut 87 from cutting or abrading the surface of the rubber cord.

The preferred forms of our invention described herein in specific detail for the purpose of disclosure and to illustrate the principles involved will suggest to those skilled in the art various changes, modifications, and substitutions that do not depart from our underlying concept. We reserve the right to all such changes, modifications, and substitutions that properly come within the scope of our appended claims.

We claim as our invention:

1. A conduit fitting of the character described, comprising: an inner cylindrical member; a shell member having one end embracing said cylindrical member, one of said members having a plurality of circumferentially spaced recesses and the other of said members having a plurality of lugs complementary to said recesses to cooperate therewith for locking said members together against both axial and rotary relative movement, said shell being split into at least two sections for release laterally from said cylindrical member, said lugs and recesses being equally spaced circumferentially whereby the two members may be engaged at various positions of relative rotation; and a clamping ring releasably embracing said shell to hold said two sections together.

2. A conduit fitting of the character described, comprising: an inner cylindrical member having a peripheral shoulder and a plurality of peripheral lugs axially spaced from said shoulder; a shell having one end embracing said cylindrical member and having a plurality of recesses complementary to and in engagement with said lugs to lock said shell to said member, said shell being split into at least two separable sections for release laterally from said member, said shell having an inclined clamping shoulder and an external thread adjacent thereto; a clamping ring threaded onto said external thread in releasable engagement with said clamping shoulder to hold said two sections together, said ring being axially movable from said thread to permit said two sections to separate; and a gland nut having an inward annular flange rotatably embracing said cylindrical member between said peripheral shoulder and said plurality of lugs.

3. A conduit fitting of the character described for incorporation in a conduit system, said fitting being designed for temporary dismantlement to permit access to the interior of the conduit system without the necessity of disturbing adjacent parts of the system, said fitting comprising: an inner member; a shell embracing said inner member; laterally engageable interlocking means carried by said shell and said inner mem-

ber, said shell being split into at least two separable sections for release laterally from said inner member; and means releasably holding said sections together around said inner member for engagement of said interlocking means to limit relative longitudinal movement between said inner member and said shell.

4. A conduit fitting of the character described for incorporation in a conduit system, said fitting being designed for temporary dismantlement to permit access to the interior of the conduit system without the necessity of disturbing adjacent parts of the system, said fitting comprising: an inner member; a longitudinally split shell having one end embracing said inner member; laterally engageable interlocking means carried by said shell and said inner member; and a clamping member releasably embracing said split shell to hold said split shell in engagement with said inner member for engaging said interlocking means to prevent relative longitudinal movement between said inner member and said shell.

5. A conduit fitting of the character described for incorporation in a conduit system, said fitting being designed for temporary dismantlement to permit access to the interior of the conduit system without the necessity of disturbing adjacent parts of the system, said fitting comprising: an inner member; a shell having one end embracing said inner member; laterally engageable interlocking means carried by said shell and said inner member, said shell being split into at least two separable sections for release laterally from said inner member; a first clamping member releasably embracing said one end of said shell to hold said sections against said inner member and engage said interlocking means; and a second clamping member for embracing the other end of said shell and releasably connecting said shell with a conduit.

6. A conduit fitting of the character described for incorporation in a conduit system, said fitting being designed for temporary dismantlement to permit access to the interior of the conduit system without the necessity of disturbing adjacent parts of the system, said fitting comprising: an inner cylindrical member; a shell split into at least two separable sections, one end of said shell embracing said cylindrical member; laterally engageable interlocking means carried by said shell and said cylindrical member, said end of said shell being provided with inclined clamping shoulders on said sections and having an external thread adjacent said clamping shoulders; a clamping ring threaded onto said external thread on said ring to engage said shoulders to hold said sections together and hold said interlocking means in engagement, said ring being axially movable from said thread past the opposite end of said shell to permit the two sections to separate; and a second ring embracing said opposite end of said shell.

7. A conduit fitting of the character described for incorporation in a conduit system, said fitting being designed for temporary dismantlement to permit access to the interior of the conduit system without the necessity of disturbing adjacent parts of the system, said fitting comprising: an inner member having a peripheral shoulder intermediate its ends; a gland nut rotatably embracing said cylindrical member and having an inwardly extending portion engaging said shoulder; a shell having one end embracing said cylindrical member adjacent said gland nut; interlocking means carried by said shell and said cy-

lindrical member, said interlocking means including a portion extending outwardly from said inner member, said inwardly extending portion of said gland nut being positioned between said shoulder and said projecting portion to retain said inner member and gland nut in assembled relation when said fitting is otherwise disassembled, said shell being split into at least two sections for lateral release from said inner member; and a clamping ring releasably embracing said shell to hold said sections together.

8. A conduit fitting of the character described for incorporation in a conduit system, said fitting being designed for temporary dismantlement to permit access to the interior of the conduit system without the necessity of disturbing adjacent parts of the system, said fitting com-

prising: an inner cylindrical member having a peripheral shoulder means; a gland nut for releasably attaching said cylindrical member to a complementary fitting, said gland nut having an inner shoulder means engaging said peripheral shoulder means; a shell having one end embracing said cylindrical member; interlocking means between said shell and said inner member, including at least one projection extending laterally outward from said inner member, said inner shoulder on said gland nut being notched to clear said projection, said shell being split into at least two separable sections for lateral release from said inner member; and means for releasably holding said two sections together.
